UNITED STATES PATENT OFFICE.

ALBERT LODGE OF PHILADELPHIA, PENNSYLVANIA, ASSIGNOR OF ONE-THIRD TO
JOHN EDWARD SMITH, OF PHILADELPHIA, PENNSYLVANIA.

FISH-PLATE.

1,076,296.

Specification of Letters Patent.

Patented Oct. 21, 1913.

Application filed April 18, 1911. Serial No. 621,776.

To all whom it may concern:

Be it known that I, ALBERT LODGE, a citizen of the United States, residing at Philadelphia, in the county of Philadelphia and 5 State of Pennsylvania, have invented new and useful Improvements in Fish-Plates, of which the following is a specification.

This invention relates to rail joint supports and more particularly to fish plates, 10 the object of the invention being to provide a fish plate having a form which will coact with both ends of the rails to be connected in the manner of a lever, the connecting bolts acting as fulcrum members.

15 Further objects of the invention will appear as the following specific description is read in connection with the accompanying drawing, which forms a part of this application, and in which:—

20 Figure 1 is a side elevation. Fig. 2 is a top plan view with parts broken away. Fig. 3 is a transverse section on the line 3—3 of Fig. 1. Fig. 4 is a similar view on the line 4—4 of Fig. 1.

25 Referring more particularly to the drawing, 1 represents suitable ties upon which the rails 2 and 3 are mounted, their abutting ends being connected by the fish plates 4 and 5 arranged upon opposite sides of the 30 rails and connected together by the bolts 6 and 7. The plates 4 and 5 have their upper edges centrally provided with bosses 9, and these bosses are adapted to be arranged below the heads of the rails at the meeting 35 edges of the said rails. The bolts 6 pass through openings in the plates that are substantially the same size as the diameter of the bolts, so as to permit no relative movement. The openings in the webs of the rails, 40 through which the bolts 6 pass may be elongated to permit of the expansion and contraction of the rails. The plates 4 and 5 are extended a suitable length in opposite directions from the bosses 9, and the said 45 plates have their upper edges, at their opposite ends, provided with bosses 11. These bosses are of a greater width than the bosses 9, so that in arranging the bosses beneath the heads of the rails a pressure must be 50 exerted upon the said ends in order to spring the bosses 11 into proper engaging position. The securing bolts 7 are arranged adjacent the ends of the plates, and are passed through elongated slots provided in the said 55 plates, and these slots are disposed verti-

cally of the said plates with relation to the rails, when the plates are positioned upon the rails. By such an arrangement it will be noted that the bolts 6 may have their securing elements screwed entirely home thereon, in arranging the plates upon the rails, while the bolts 7 are loosely passed through their respective openings, and after the ends of the plates have their bosses sprung into engagement beneath the heads of the rails 60 the nuts for the bolts 7 are screwed entirely home. The bolts 7, and the nuts therefor, are adapted to serve only as means for preventing the outward springing of the ends of the plate, but the bolts 6 and their 65 engaging nuts are not only adapted to prevent the lateral or outward movement of the plates at the central portion thereof, but are also adapted to prevent a vertical movement, in either direction of the central 70 portions of the said plates, and so, as previously stated, retaining the bosses 9 tightly in engagement beneath and with the rail heads at the joint of the rails.

75 By an arrangement, as above described, 80 it will be noted that the bosses 11 spring the plates 4 and 5 sufficiently to at all times force and retain the bosses 11 in proper engagement with the heads of the rails at the joint of the rails, so that danger of a 85 sinking or downward movement of the joint is effectively overcome. It will be further noted that should the rails, at their points of engagement by the bosses 11, and incident to the weight of the rolling stock causing 90 a downward flexure of the rails at these points, the said bosses will give with the rails, (in which instance the bolts 6 serve as fulcrum points), and exert a tension to force the bosses 9 more tightly into engagement 95 beneath the heads of the rail ends. The plates are of a lesser width than the fishing spaces between the heads 10 and the base flanges of the rails.

Having thus described the invention, what 100 I claim is:

In combination with meeting ends of two railway rails, of a fish plate for connecting the rail ends, said plate comprising a flat bar of a lesser width than the fishing spaces 105 of the rails, said bar having its upper edge centrally provided with a projecting boss, the plate having bolt openings disposed adjacent the boss, bolts for the openings and connected with the rails and adapted to 110

force the boss into tight engagement beneath the heads of the rails at the ends of the said rails, the opposite ends of the fish plate having projecting bosses of a greater height than the central projecting boss, the said plate adjacent the end bosses being provided with elongated openings, bolts passing through the openings and through the webs of the rails, and the said openings adapted to permit of the end bosses being sprung downwardly to engaging position

with the heads of the rails to force the central boss more tightly into engagement, and the bolts of the elongated openings provided with securing members to prevent the lateral movement of the ends of the plate. 15

In testimony whereof I affix my signature in presence of two witnesses.

ALBERT LODGE.
